UNITED STATES PATENT OFFICE.

FREDERICK S. BRAGG, OF CORNING, NEW YORK, ASSIGNOR OF ONE-HALF
TO AUSTIN LATHROP, OF SAME PLACE.

SPARK-ARRESTER.

SPECIFICATION forming part of Letters Patent No. 365,234, dated June 21, 1887.

Application filed December 4, 1886. Serial No. 220,695. (No model.)

To all whom it may concern:

Be it known that I, FREDERICK S. BRAGG, of Corning, in the county of Steuben, in the State of New York, have invented new and 5 useful Improvements in Spark-Arresters for Locomotives, of which the following, taken in connection with the accompanying drawings, is a full, clear, and exact description.

This invention is a specific improvement of 10 the cinder-escape and draft-regulating devices shown in my Patent No. 325,907, dated September 8, 1885, and also shown in a modified form in a pending application for patent, Serial No. 218,257, filed November 8, 1886. In either 15 of the said prior devices the air-inlet was made to communicate with the smoke-box through the medium of the cinder-discharge spout.

Although I have derived great advantages 20 from the aforesaid arrangement of parts, yet by practical experience I have found that by making the air-inlet to the smoke-box below the screen or wire-netting, as heretofore, but 25 separate and distinct from the cinder-discharge opening or spout, I not only enhance said advantages, but also render my invention applicable to a locomotive smoke-box without disturbing the existing cinder-spout; hence my 30 present invention consists, essentially, in the combination, with the smoke-box of a locomotive, of a cinder-discharge opening and an air-inlet separate and distinct from the aforesaid opening and below the screen, as hereinafter more fully described, and specifically set forth 35 in the claims.

In the accompanying drawings, Figure 1 is 40 a side elevation of a locomotive smoke-box, partly shown in section to better illustrate my invention; and Fig. 2 is an enlarged detached longitudinal sectional view of the spring-coupling by which the damper of the air-inlet is connected with its operating-lever.

A represents the smoke-box of a locomotive, formed with the front extension, A', which is 45 at present coming into extensive use on coal-burning locomotives. A wire-netting, N, is extended across the upper part of the smoke-box, and reaches from the flue-sheet B part way into the smoke-box extension A', and the nozzles of the exhaust-pipes P project through 50 the netting N from the under side thereof, so as to produce a suction upward through the

netting by the exhaust of the steam from the pipes P, the netting serving to arrest the sparks in the smoke-box.

C denotes the cinder-discharge spout attached 55 to the under side of the smoke-box A, or its extension A', the shell of which is provided with an opening, by which the said smoke-box communicates with the spout. The lower end of the spout C has hinged to it a gate, D, which 60 is counterbalanced, so as to normally stand in a position to close the spout. Said spout is located intermediate the length of the smoke-box or its extension preferably nearer to the front end thereof than the smoke-stack I, so as 65 to obtain sufficient room between the spout C and flue sheet B to allow the cinders to cool before they reach the spout.

Between the spout C and front end of the smoke-box extension A' the bottom or lower 70 portion of the latter is provided with the air-inlet port L, and with a damper, a, by which to control the ingress of air to the interior of the smoke-box. The result of this arrangement is that when the engine is in motion the 75 inflowing air current (represented by arrows in the drawings) partly drives the heat back against the flue-sheet, and thus augments the heating capacity of the boiler. At the same time the fine dust is allowed to be drawn up 80 through the screen or netting N and escape through the stack, as indicated by the fine broken lines in Fig. 1 of the drawings, while the cinders (represented by heavy dots) are cast forward by the draft of the smoke-stack and 85 finally enter the spout C. The cool air current sweeping over the cinders in their approach to the spout serves to cool the cinders. They can be discharged from the spout C whenever 90 desired by opening the gate D, and thus the smoke-box can be kept comparatively cleaned from cinders while the engine is in motion. Aside from this advantage the draft through the stack can be moderated at will by opening 95 to a greater or less extent the damper a of the air-inlet L, and by the moderation of said draft economy in the consumption of fuel is obtained.

I do not limit my invention to the location of the air-inlet L in the bottom of the smoke-box or its extension, as it is obvious that a like 100 or similar effect can be produced by locating the said inlet at or near the base of the front

end plate, *d*. It is, however, essential to locate said inlet below the spark-arresting screen or diaphragm, and its best location is between the cinder-spout and front end of the smoke-box.

5 The gate *D* and damper *a*, I control by one and the same rod, *f*, connected with two bell-crank, *g h*, one of which latter has one arm connected with the gate *D* by a rod, *r*, and the other bell-crank has one of its arms connected with the damper *a* by a spring-coupling, *i*, the construction of which is shown in detail in Fig. 2 of the drawings.

10 The connection of the bell-crank *g* with the controlling-rod *f* has sufficient play to allow said rod to open the damper *a* to a certain extent without moving the gate *D*, and a further movement of the rod *f* then opens the said gate, the spring-coupling *i* permitting said 15 further movement of the rod *f* without strain of the damper *a*.

Having described my invention, what I claim as new, and desire to secure by Letters Patent, is—

20 25 1. The combination, with the smoke-box of a locomotive provided with the spark-arresting screen or diaphragm, of a cinder-discharge

opening, and an air-inlet to said smoke-box below the screen and separate and distinct from the cinder-discharge opening, as set forth.

2. The combination, with the smoke-box of a locomotive, provided with a spark-arresting screen or diaphragm, of a cinder-discharge opening, and an air-inlet to said smoke-box at the front end thereof and below the spark-arresting screen or diaphragm, as set forth and shown.

3. The combination, with the smoke-box of a locomotive, of a cinder-discharge spout provided with a gate, an air-inlet separate and distinct from said spout, a damper connected with the air-inlet, levers for operating said gate and damper, and a controlling-rod connected with the aforesaid levers, substantially as described and shown.

In testimony whereof I have hereunto signed my name and affixed my seal, in the presence of two attesting witnesses, at Corning, in the county of Steuben, in the State of New York, this 2d day of December, 1886.

FREDERICK S. BRAGG. [L. S.]
